UNITED STATES PATENT OFFICE.

ARTHUR E. FINERUD, OF LANESBORO, MINNESOTA, ASSIGNOR TO EDWARD E. FINERUD, OF LANESBORO, MINNESOTA.

LEAF-SPRING SPREADER.

1,279,528.

Specification of Letters Patent. Patented Sept. 24, 1918.

Application filed February 15, 1917. Serial No. 148,766.

To all whom it may concern:

Be it known that I, ARTHUR E. FINERUD, a citizen of the United States, and a resident of Lanesboro, in the county of Fillmore and

5 State of Minnesota, have invented a certain new and useful Improvement in Leaf-Spring Spreaders, of which the following is a specification.

The present invention relates to a device 10 for spreading apart the leaves of a multi-leaf spring for the purpose of lubricating and cleansing the latter.

An object of the present invention is to provide a spreader of this character with 15 a pivoted jaw, the latter being so constructed that when moved into engagement with the spring it will be held yieldingly from swinging past the center of its pivot in either direction, and may be swung into 20 and out of operation in either direction.

The invention further aims at the provision of a spreader having a wedge jaw for engagement between the leaves of the spring, and to provide the jaw with means 25 for directing and conveying a lubricant into the space between the spread-apart leaves of the spring.

The above, and various other objects and advantages of this invention will be in part 30 described, and in part understood, from the following detailed disclosure of the present preferred embodiment, the same being illustrated in the accompanying drawing wherein:

35 Figure 1 is a side elevation of a leaf spring spreader constructed according to the present invention.

Fig. 2 is a section taken longitudinally through the spreader, disclosing in section 40 a multi-spring with the spreader applied thereto.

Fig. 3 is a top plan view of the spreader, the dotted lines disclosing the position of the spring when the spreader is applied 45 thereto.

Fig. 4 is a transverse section taken on the line 4—4 of Fig. 1, looking in the direction of the arrows and showing the construction of the pivoted oil-feeding jaw.

50 Referring to this drawing, 10 designates

the body part or yoke of the spreader which is substantially U-shaped, and having on one upturned arm the longitudinally arranged bearing 11.

The opposite upturned arm of the yoke 55 10 is provided with a post or pivot pin 12 and an annular shoulder or seat 13 surrounding the base of the post. The outer extremity of the post 12 is reduced and externally screw-threaded to provide a shank 60 or projection upon which may be detachably carried a clamping nut 14 or the like.

The body part 10 carries in its opposite end a fixed jaw 15 and a movable or clamping jaw 16. The jaw 15 is in the form of 65 a tapering hardened end constituting the inner terminal of an elongated set-screw 17, provided with an enlarged knurled or otherwise suitably roughened head 18 at its outer end. The set-screw 17 is provided with a 70 lock-nut 19 threaded upon the set-screw between the bearing 11 and the head 18, and adapted to be jammed against the outer end of the bearing 11 to lock the set-screw 17 when adjusted.

The movable jaw 16 is in the form of a wedge constituting the inner extremity of a lever 20 which is apertured intermediate its ends for pivotal engagement upon the post 12. The wedge jaw 16 is substantially chisel shaped and provided with a straight-line spring-engaging edge 21 and upper and lower substantially flat converging faces. The outer end of the lever 20 is provided with a handle portion 22 of any 80 suitable configuration, and which is preferably offset from the pivoted portion of the lever 20. The head 18, the locking nut 19, and the handle 22 are preferably provided with knurled or milled surfaces to afford a 85 firm gripping of the same by the fingers and the hand for manipulating the various parts of the spreader.

The retaining nut 14 is provided at its inner end with an annular flange 23 of substantially the diameter of the base flange 13 of the yoke, and which is held in spaced relation with respect to the base flange 13 by means of a shoulder 24 formed annularly around the inner end of the shank 100

of the post 12. The lever 20 is provided with opposed flat faces adapted for engagement against the flanges 13 and 23, and the lever 20 may be placed on the post 12 in the position shown in the drawings, or the lever 5 may be reversed, if so desired.

The movable jaw 16 is provided in one or both sides with an oil-receiving and conveying channel or recess 25 which extend 10 to, and interrupts the straight-line edge 21 of the movable jaw. These grooves 25 extend to a considerable extent in the converging opposed faces of the wedge-shaped jaw 16, and are preferably enlarged at their 15 outer ends for the reception of a lubricant, such as oil, adapted to be fed to the space between the leaves of the spring.

In use, the fixed jaw 15 is adjusted to the desired position in the bearing 11, and is 20 then secured from movement by means of the lock-nut 19. The yoke 11 is now placed about a spring A of the leaf type with the apex of the conical fixed jaw 15 between the edges of two adjacent leaves of the spring. 25 The spring A is now clamped in the yoke by swinging the handle 22 outwardly to turn the lever 20 about the post 12 and bring the movable jaw 16 into contact with the opposite side of the spring A. As the lever 20 is 30 forced around the pivot 12 the jaw 16 is forced at its straight-line edge 21 between the leaves of the spring A, and the latter is shifted laterally onto the tapering fixed jaw 15. Pressure is thus equalized against the 35 opposite sides of the spring A, and the jaws 15 and 16 bind with the same force between the adjacent leaves of the spring. When the lever 20 is swung into a position substantially at right angles to the longitudinal 40 axis of the spring A, the straight-line edge 21 of the movable jaw 16, and the opposed relatively flat faces of the jaw engage across their surfaces against the leaves of the spring A and thus hold the lever 20 yieldingly from passing in either direction beyond the center of the pivot 12. This peculiar formation of the movable jaw 16 thus holds the lever 20 in locking position and prevents it from accidentally swinging, by 45 vibration or the like, in either direction to disengage the jaws from the spring A. A lubricant may now be poured or dropped into the uppermost groove 25, and the latter guides the lubricant to the chisel edge of 50 the movable jaw 16 and there deposits the lubricant between the adjacent spread-apart leaves of the spring.

The terms "upper" and "lower" have been used in the above description with reference 60 to the position in which the leaf spring spreader is shown in the present drawing, and it is to be understood that the device will work equally as well when inverted, or placed at any angle which is required for

the application of the spreader to the leaf 65 spring.

It is of course understood that various changes and modifications may be made in the details of construction of the above-described embodiment of the invention without departing from the spirit thereof, and being restricted only by the 70 scope of the following claims.

I claim:—

1. A leaf spring spreader having a jaw 75 adapted to engage between adjacent leaves of the spring, said jaw being provided in its exterior face with an oil groove leading into the space between the separated leaves of the spring and adapted to deposit a lubricant in 80 said space.

2. In a leaf spring spreader, the combination of a body portion, an adjustable fixed jaw carried by the body portion, and a pivoted jaw mounted on the body portion, said pivoted jaw having its spring-engaging end terminating in a relatively straight-line abutting edge extending at right angles to the longitudinal axis of the jaw, and lying substantially in the transverse plane of the 90 jaw, said straight-line abutting edge being adapted for engagement throughout its length with a spring to yieldingly hold said pivoted jaw from swinging past center when moved into engagement with the spring. 95

3. In a leaf spring spreader, the combination of a yoke provided upon one end with a bearing, and having a post upon its opposite end with an annular flange at the base of the post, a set-screw adjustably mounted in said 100 bearing, a lock-nut on said set-screw for engagement with the bearing to secure the set-screw in adjusted position, said set-screw being provided with a tapering inner end forming a fixed adjustable jaw for engagement with one side of a leaf spring, a lever pivoted upon said post and having a handle upon one end and a wedge-shaped jaw on its opposite end having relatively 105 flat spring engaging faces to yieldably hold the lever from movement past center in either direction, and a clamping nut carried on the outer end of the post and provided with an annular flange adapted for engagement with said lever to hold the same between the flange on the nut and the flange at 110 the base of the post.

4. In a leaf spring spreader, the combination of a yoke, a fixed jaw carried in one side of the yoke, and a pivoted jaw mounted 115 upon the opposite side of the yoke and having a relatively straight line spring-engaging edge adapted for insertion between adjacent leaves of the spring, said movable jaw having an oil groove in its exterior face 120 leading to and interrupting said straight line edge, to provide spaced-apart spring engaging shoulders to hold the pivoted jaw 125

from movement past center in either direction, the outer end of said oil groove terminating in an enlarged recess in the face of the jaw, to receive a lubricant to be fed to the space between the adjacent leaves of the spring.

5. A leaf spring spreader including a

wedge member adapted to be inserted between adjacent leaves of a spring, said member having in its exterior face an oil groove 10 leading into the space between the separated leaves of the spring and adapted to deposit a lubricant in said space.

ARTHUR E. FINERUD
